BIN WITH MOVABLE BOTTOM

Samuel Saul, Jr., Pittsburgh, Pa.

Application August 22, 1945, Serial No. 612,058

7 Claims. (Cl. 220—93)

1

This invention is for an improvement in bins or boxes, and is particularly applicable but not restricted to portable bins or boxes of a type commonly used in industrial establishments in assembly line operations.

In many types of manufacturing operations, portable bins or boxes are conveniently used to bring and retain a supply of parts to be incorporated in some equipment being there manufactured, the bins or boxes, full of parts, being brought to a particular assembly line or other station. When one box or bin is empty, another is waiting to be brought into place. When the bin or box is full the operator has easy access to those on top, but as the supply is exhausted, the operator must reach further and further down to remove the remaining pieces. Similar bins or boxes may also be used to receive and transport parts from one station to another, in which case the operator starts with an empty box and fills it, often with pieces requiring care in handling. In such instance, when the box is empty, he must reach clear to the bottom of the box to lay the first pieces in it, reaching a progressively less distance as the box or bin becomes full.

The present invention provides an improved box or bin for this and like purposes wherein the bottom of the bin "floats" up and down depending upon whether it is full or empty, adapting its level always to the amount of material in the bin. Hence the distance that the operator must reach, either in unloading or loading is uniform.

The invention further provides such a bin or box of strong, simple construction in which the movable bottom will not tip and bind due to uneven distribution of the load thereover.

My invention may be more fully understood by reference to the accompanying drawings, in which:

Fig. 1 is a longitudinal vertical section through a bin embodying my invention;

Fig. 2 is a staggered transverse section thereof, the view being in about the line II—II of Fig. 3;

Fig. 3 is a perspective view of the bin;

Fig. 4 is a perspective view of the movable bottom; and

Fig. 5 is a detail view, on a larger scale, of one of the corner guides, the view being a vertical section.

Referring to the drawings, the bin or box is

2

preferably of rectangular form and is formed of heavy gauge sheet metal. It has two end walls 2, a high side wall 3, and a low side wall 4 which is normally turned toward the operator and which is several inches shorter in height than the side 3 or ends 2. The box has a bottom 5 formed of sheet metal and reinforced by intersecting angles 6 as disclosed in my United States Patent No. 2,316,892, granted April 20, 1943. Conveniently the bottom of the box may be provided with castors 7 and 8, castors 8 being swiveled. The castors provide for the movability of the box and support it so that a transfer apparatus can be put under it if desired.

15 Near the bottom of the box at each end and on the outside thereof is a transverse angle 9 providing a horizontally extending supporting ledge. Extending up the ends of the box at each corner are sheet metal housings 11 which are preferably 20 substantially square in section. A rod 12 connected between these housings provides a convenient handle for manipulating the bin. In each of the housings 11 there is fixed a vertical tube 13. The tube 13 is provided with a plug at 25 its lower end into which is screwed a bolt 14, the bolt 14 passing through the supporting flange 9. The top of the tube has a plug therein into which is screwed a bolt 15, the bolt 15 passing through an angle bracket 16 that is secured to the end wall 30 of the bin. The tubes 13 provide rigid guide posts of light construction, and around each post there is a long compression spring 17. The top of the compression spring bears against the under side of a flanged guide member 18, this guide member having a flanged top 19 and depending sleeve 20 that has a sliding fit on the tube 13. Downward movement of the guide is resisted by the compression spring 17.

Inside the box there is a false bottom structure 40 comprising a sheet metal plate member 21 having downwardly turned side and end flanges as shown in Fig. 4. This plate is supported on parallel cross rods 22, the cross rods having brackets 23 thereon by means of which the plate 21 is bolted to them. The cross bars 22 are longer than the greatest width of the bin and the end walls of the bin are provided with parallel vertical slots 24 through which the ends of the cross bars 22 project, the ends of the cross bars 22 providing projections which rest on the guide members 18.

The slots 24 extend from a point just under the angle bracket 16 to the point designated 25, which is the lower limit of travel of the false bottom. The false bottom or floating bottom is thus resiliently supported at each corner on one of the vertically movable guide elements 18, and it can be forced downwardly against the compression of the spring 17. The slots 24 provide guideways for the ends of the bars 22 and limit the upward travel of the bottom under the pressure of the springs. When the bottom is pushed down so that the cross bars 22 are at the bottom limits 25 of the slots 24, the sleeve elements 20 of the guides 18 will contact the flanges 9 so that further downward movement is prevented.

As heavy articles are charged onto the bin, the floating bottom 21 will be forced down, going down as the load resting on the bottom increases. Likewise, when the load is removed piece by piece from the top of the bin, the bottom 21 will rise, thereby making it unnecessary for the operator to reach down into the bin as the supply becomes exhausted, or while he is loading the bin.

The guide elements 18 comprising the flange 19 and the sleeve 20 have a long sliding contact on the guide posts of tubes 13. Hence these guides can move only axially of the tube, i.e., in a vertical direction, and they cannot be tilted or canted so as to bind on the posts. The projecting ends of the bars 22 merely rest on these supporting guide elements and no binding action can result from unequal distribution of the load on the bottom 21. The flanged side edges of the bottom 21 are preferably out of contact with the vertical walls, the slots 24 being so positioned and of such proportions that the bottom 21 will float up and down freely between the front and back side walls without contacting either. The guide posts 13 in addition to causing the floating bottom to move up and down in a plane even though there may be uneven loading, serve to confine the spring 17 so that as it compresses, it will not bow or buckle away from its axis to any appreciable extent.

The bin can be cheaply constructed. Access can also be readily had to any of the guides for replacing them or replacing a spring. To remove or replace the springs it is merely necessary to unbolt one of the brackets 16 and remove the bolt 15. Then by removing the bolt 14 the entire tube 13 may be removed. This leaves the guide unevenly supported, and by pushing down on one end of the bottom, the bottom can be inclined to an angle where the projecting ends of the cross bars 22 can be maneuvered out of the slots. A similar operation may be performed in assembling the structure.

Aside from the simplicity, the invention provides a bin in which the bottom moves up and down according to the load on it without binding and without adverse effect due to unequal loading. The springs which support the bottom and also the guides, are entirely outside of the bin so that they are protected from damage and do not occupy any storage space within the bin itself.

While I have specifically described and illustrated one present preferred embodiment of my invention, it will be understood that this is by way of illustration and that various changes and modifications in the construction may be made within the contemplation of my invention and under the scope of the following claims.

I claim:

1. A bin comprising a casing, a movable bottom in the casing, a plurality of guide posts extending

vertically of the casing having guide sleeves thereon, which sleeves have a sliding fit on the posts, springs surrounding the guide posts and bearing against the sleeves and extensions on the movable bottom resting on the sleeves for normally supporting the bottom.

2. A bin comprising a four-sided casing, a vertically movable bottom member in the casing having a working fit therein, guide posts adjacent each corner of the casing, guide sleeves slideable on the posts and having a sliding fit thereon, means at each corner of the bottom member engaging one of the sleeves whereby the bottom member and sleeves move vertically together, and springs resiliently urging the bottom and sleeves upwardly.

3. A bin comprising a rectangular casing having end walls and front and rear walls, two opposed walls having a pair of spaced vertically extending slits therein, a vertically movable bottom member within the casing having a working fit therein, the bottom member having extensions which extend through said slits, guide sleeves outside the casing with which the said extensions are engaged, guide posts outside the casing on which the sleeves have a sliding fit, and springs surrounding the guide posts resiliently supporting the sleeves.

4. A bin comprising a rectangular casing having end walls and front and rear walls, two opposed walls having a pair of spaced vertically extending slits therein, a vertically movable bottom member within the casing having a working fit therein, the bottom member having extensions thereon which extend through said slits, guide sleeves outside the casing with which the said extensions are engaged, guide posts outside the casing on which the sleeves have a sliding fit, springs surrounding the guide posts resiliently supporting the sleeves, and a housing outside the casing enclosing each of the guide posts and its spring.

5. A bin comprising a rectangular casing having front and rear walls and having end walls, each of the end walls having a pair of vertically extending slots therein at each side of the center thereof, a vertically movable bottom member in the casing having a free working fit inside the casing, projecting elements on the bottom member extending through the slits, guide sleeves outside the casing under each of the said projecting elements for supporting the same, a fixed guide post on which each of the said guide sleeves has a sliding fit, and a spring surrounding each guide post and resiliently supporting the guide sleeve which is slideable on said post.

6. A bin comprising a casing having front and rear walls and having opposed end walls, the two end walls and the rear wall being higher than the front wall, a bottom member in the casing movable vertically with respect thereto, the bottom member having extensions at each end thereof, the end walls having vertically extending parallel slots therein through which the projections extend, said slots limiting the upward travel of the movable bottom member, a supporting post on the outside of the casing and adjacent each slot, a guide sleeve having a sliding fit on each post, the projections on the movable bottom member which extend through the respective slots being engaged with the several guide sleeves for movement up and down with the guide sleeve, and compression springs surrounding each of the guide posts and resiliently supporting the guide sleeves against downward movement.

7. A bin comprising a casing, a bottom member in the casing movable vertically up and down therein, projections on the bottom extending laterally through the casing at a plurality of points, the casing having vertical slots to accommodate and guide such projections, guide sleeves, guide posts on which the sleeves move secured to the outside of the casing adjacent said slots, the guide sleeves supporting the said projections and having a sliding fit on the posts, and 10 spring elements surrounding the guide posts for resiliently urging the sleeves upwardly.
